UNITED STATES PATENT OFFICE

154,778

DESIGN FOR A COMBINED CIGARETTE HUMIDOR AND ASH TRAY

Julius A. Hussar, Cleveland, Ohio

Application February 3, 1948, Serial No. 144,240

Term of patent 7 years

(Cl. D85—2)

To all whom it may concern:

Be it known that I, Julius A. Hussar, a citizen of the United States, residing at Cleveland, in the county of Cuyahoga and State of Ohio, have invented a new, original, and ornamental Design for Combined Cigarette Humidor and Ash Tray, of which the following is a specification, reference being had to the accompanying drawing, forming part thereof.

Fig. 1 is a side elevational view of a combined cigarette humidor and ash tray showing my new design; and Fig. 2 is a top plan view thereof.

I claim:

The ornamental design for a combined cigarette humidor and ash tray, as shown.

JULIUS A. HUSSAR.
